(57) **CLAIM**

We claim the ornamental design for a lower receiver for a firearm, as shown and described.

DESCRIPTION

FIG. 1 is front perspective view of a lower receiver for a firearm;

FIG. 2 is a rear perspective view of the lower receiver of FIG. 1;

FIG. 3 is a left side view of the lower receiver of FIG. 1;

FIG. 4 is a right side view of the lower receiver of FIG. 1;

FIG. 5 is a rear view of the lower receiver of FIG. 1;

FIG. 6 is a front view of the lower receiver of FIG. 1;

FIG. 7 is a top view of the lower receiver of FIG. 1;

FIG. 8 is a bottom view of the lower receiver of FIG. 1;

FIG. 9 is a front perspective view of a left half of the lower receiver of FIG. 1;

FIG. 10 is a rear perspective view of a left half of the lower receiver of FIG. 1;

FIG. 11 is a front perspective view of a right half of the lower receiver of FIG. 1; and,

FIG. 12 is a rear perspective view of a right half of the lower receiver of FIG. 1.

The broken lines shown in the figures are for illustrative purposes only and form no part of the claimed design.
